UNITED STATES PATENT OFFICE.

THOMAS H. SYMINGTON, OF ROCHESTER, NEW YORK.

ANTIFRICTION SIDE BEARING.

1,178,689.

Specification of Letters Patent. Patented Apr. 11, 1916.

Application filed May 8, 1914. Serial No. 837,166.

To all whom it may concern:

Be it known that I, THOMAS H. SYMINGTON, a citizen of the United States of America, residing at the city of Rochester, county 5 of Monroe, State of New York, have invented certain new and useful Improvements in Antifriction Side Bearings, of which the following is a specification.

The subject of this invention is an anti-friction side bearing for cars.

The nature and operation of side bearings is well understood. Every such bearing consists of two plates, one over the other, and one or more rollers between the plates, the 15 top plate being secured to the bottom of the car bolster and the bottom plate to the truck, so that the rollers between the plates, rolling on both the top and bottom plates, serve to take up or reduce the friction between the truck and bolster when the trucks 20 swing relatively to the car body in rounding bends and the like.

In the ordinary construction, the top plate forms the bottom of an inverted box 25 which is secured to the car bolster, and this box holds the rollers. Whenever the bearing comes into action, the rollers tend to travel toward the end of the box and one of the problems encountered in the construction 30 of these bearings is the provision of means for returning the rollers to a central position in the box so that they may be available as anti-friction members at every swing of the truck. To accomplish this, ad- 35 vantage is taken of the swaying of the car body relatively to the truck, for every time the car sways to one side, the weight is lifted from the bearing on the opposite side of the car. This affords an opportunity to 40 return the rollers to central position and to do this various means are provided.

The present invention relates to a new and improved means for centering the rollers when they are thus released. For this 45 purpose, I have provided a flexible journal which at its ends is suitably connected to the box near its longitudinal center. Thus, when the rollers leave the center of the box, the journal is flexed and when the car sways 50 so that the rollers are released, the flexible journal immediately acts to return the rollers to central position.

While I have shown the flexible journal in the present instance as consisting of a 55 spiral spring which extends through the roller in the manner of an axle, I desire to

have it understood that this form of the invention is shown merely for purposes of illustration and the flexible member may be constructed in a variety of forms within 60 the scope of my invention.

In the accompanying drawing I have illustrated the preferred form of my invention.

Figure 1 is a view half in front elevation and half in vertical central cross-section, 65 the section being taken on the line of the axis so that the view shows the box, the roller and the flexible journal of the invention; Fig. 2 is a side elevation, half in longitudinal section; and Fig. 3 is a bottom 70 plan.

Referring to the drawing by numerals, each of which is used to indicate the same or corresponding parts in the different figures. The side bearing consists of a box 1, having 75 integral flanged members 2 by means of which it is secured to the body bolster, not shown, a bearing plate 3 within the box, a bearing plate 4 secured to the truck, or vice versa, and a roller 5 between the plates and adapted to bear on both plates when the weight of the car rests upon the box 1. In the form of the invention shown, the diameter of the roller is about half the length of the box and of the bearing plates, so that 80 the roller moves back and forth as the truck swings.

To return the roller to central position when it is released, as heretofore described, I provide a flexible journal 6 which is connected at one or both ends to the box or other suitable member, near the center of its length. In the present instance, this connection consists of sockets 7 in the sides of the box in which the ends of the journal 6, 95 which is in the form of a spiral spring extending through the roller after the manner of an axle, are seated. To give freedom of motion to the roller, this socket is expanded in a horizontal plane as shown in Fig. 3, and the opening 8 in the roller through which the member 6 passes, is also widened or belled at the mouth, leaving the spring or flexible journal free to be flexed between its 100 ends to a point near the center.

The flexible member 6 may be introduced in any suitable manner, but this is preferably done by opening one of the sockets and providing a suitable cap. In the present instance I have shown one socket open in the direction of the axis at 9, the opening being 110 filled with type metal to close it after the in-

troduction of the spring. In this way dis-
placement by vibration is prevented and the
plug may be easily removed and the spring
taken out when occasion requires.

5 I have thus described what I at present
consider to be the preferred form of my in-
vention, in order that the nature of the de-
vice may be fully understood and those
skilled in the art may be enabled to con-
10 struct and operate it. However, I desire to
have it understood that the structure thus
set forth may be variously developed and
embodied within the scope of my invention.

What I claim and desire to secure by
15 Letters Patent is:

1. A side bearing for cars having a box
with a roller therein, the roller having an
axial opening, a bearing socket on each side
of the box, a spring having one of its
20 ends seated in each bearing socket and ex-

tending through the opening in the roller,
the sockets having the openings enlarged at
the mouth, the axial opening in the roller
being likewise enlarged near the end faces
of the roller.

25

2. In a side bearing for cars having a box
with a roller therein and a socket at each
side of the box, the roller having an axial
opening, a spring having one of its ends
seated in each socket and extending through 30
the opening in the roller but free to move
into and out of the bottom portions of the
sockets to permit the spring to be flexed to
respond to the traverse of the roller.
